UNITED STATES PATENT OFFICE.

JOHN C. ERNST, OF FLEMINGTON, NEW JERSEY, ASSIGNOR OF TWO-THIRDS
TO FRANK B. MALLORY AND WILLIAM W. HAWKE, OF SAME PLACE.

BICYCLE-BRAKE.

SPECIFICATION forming part of Letters Patent No. 604,030, dated May 17, 1898.

Application filed September 19, 1896. Serial No. 606,394. (No model.)

To all whom it may concern:

Be it known that I, JOHN C. ERNST, a citizen of the United States, residing at Flemington, in the county of Hunterdon and State of New Jersey, have invented certain new and useful Improvements in Bicycle-Brakes; and I do hereby declare the following to be a full, clear, and exact description of the invention, such as will enable others skilled in the art to which it appertains to make and use the same.

My invention relates to brakes for bicycles.

It consists of certain novel constructions, combinations, and arrangements of parts, as will be hereinafter described and specifically claimed.

In the accompanying drawings, Figure 1 is a side elevation, partly in section, of a portion of a bicycle, showing my improved invention applied thereto. Fig. 2 is an enlarged vertical section of a handle-bar and handle with my invention applied thereon. Fig. 3 is a transverse section through the line xx of Fig. 2. Fig. 4 is a detail view of the balls or flexible connecting means employed in the brake. Fig. 5 is a detail view of portion of a wheel showing, a brake-shoe provided with a brush; and Fig. 6 is a detail perspective view of a portion of the plunger and its actuating means.

30 A in the drawings represents the handle-bar of the bicycle, which is provided with a longitudinal slot a near its outer end.

B represents a revoluble sleeve to which the handhold C is firmly secured, so as to revolve therewith. The revoluble sleeve is provided with a spiral-shaped or worm slot D. The pitch of the slot may be steep at the beginning and reduced to a very gradual one near the outer end of the same, as shown in the drawings, so that the brake can be applied with a quick start forward by a slight turn of the handhold or the pitch may be uniform throughout and the brake be applied with great power to the tire of the wheel and 45 cannot work backward and release the brake without being positively turned by the hand. A plunger-rod E, also head e, operates in the handle-bar A. The plunger-rod is also provided with a transversely-arranged pin e', 50 which works in the longitudinal slot a in the handle-bar and in the spiral slot D. It is ob-

vious that when the sleeve B is revolved forward or backward the pin will traverse the slots a and D and be forced to travel in a longitudinal direction through the elongated slot 55 a in the handle-bar A. To facilitate the movement of the pin through the spiral slot D, the pin e may be provided with an antifriction-roller d, which will bear against the walls of the slot a , and also be provided with a guid-ing-shoe e^2 , which bears upon the walls of the slot D.

F represents a tube or guideway which extends through the head-post and into the handle-bar of the machine and directs the movement of the balls G. These balls bear upon the upper end of the brake-shoe H, which latter is attached to the brake-shoe I. By the use of balls an operating means between the plunger-rod and the brake-shoe is secured, 65 which can be easily moved through the curved portions of the handle-bar and head. In Fig. 4 I have shown the connections made in the form of dumb-bells as an equivalent of the balls.

J represents a spring which is connected to the brake-shoe rod and bears with its lower end against the brake-shoe for returning the brake-shoe when the plunger-rod is moved backward.

In Fig. 5 I show the brake-shoe I, provided with a scraping-brush.

One serious objection to the brakes now in use is that the tire collects mud and sometimes sharp pieces of stone which adhere to 85 it, so that when the brake is applied the tire is liable to be cut or punctured by the same. To overcome this and prevent all danger of the tire being punctured from the use of the brake, I contemplate providing the brake-shoe with a safety-scraper or brush, as shown, which is arranged so as to come in contact and thoroughly clean the tire before the brake touches it, and when the brake is released the brush will be automatically lifted from 90 the tire, so as not to cause friction, and thus prevent any danger to the tire.

The operation of the brake will be obvious from the foregoing description and an inspection of the drawings. It will be observed 100 that when the brake is applied the spring J cannot throw the pin back through the spiral

slot and that the brake can only be taken off by turning the sleeve backward. This is important, as it secures a perfectly safe brake which does not have to be constantly held in place by the hand or by any other auxiliary locking means. As soon as the handle is rotated to release the brake the spring will automatically raise the brake-shoe from off the tire.

10 Having now described my invention, what I claim as new, and desire to secure by Letters Patent, is—

15 1. In a bicycle-brake, the combination of a handle-bar provided with a longitudinal slot, a revolute sleeve provided with a spiral slot, a plunger provided with a pin which operates in said slots, a brake-shoe, balls interposed between the brake-shoe and the plunger for pushing the brake-shoe against the tire of the 20 wheel and means for returning the brake-shoe, substantially as described.

25 2. In a bicycle-brake, the combination of a handle-bar provided with a longitudinal slot, an independently-removable sleeve slipped on the handle-bar and provided with a spiral slot which extends through the walls of the sleeve, a handhold secured to said removable sleeve, a plunger provided with a pin, a brake-shoe, balls interposed between the brake-shoe 30 and the plunger for forcing the brake-shoe against the tire of the wheel, and a spring for returning the brake-shoe, substantially as described.

35 3. In a bicycle-brake, the combination of a handle-bar provided with a longitudinal slot, a revolute sleeve fitted on the handle-bar, and provided with a spiral slot, a handhold secured to said sleeve whereby it may be

turned, a plunger provided with a pin which operates in the said slots, a brake-shoe, and 40 balls interposed between the brake-shoe and the plunger for pushing the brake-shoe into operative position, and means for returning the brake-shoe, substantially as described.

4. In a bicycle-brake, the combination of a 45 handle-bar provided with a longitudinal slot, a revolute sleeve fitted on the handle-bar, and provided with a spiral slot, a handhold secured to said sleeve, a plunger provided with a pin which operates in the said slots, a 50 roller on said pin which bears against the walls of the slot in the handle-bar, and a shoe which bears upon the walls of the slot in the sleeve, a brake-shoe, flexible means interposed between the brake-shoe and the plunger 55 for pushing the brake-shoe into operative position, and means for returning the brake-shoe, substantially as described.

5. In a bicycle-brake, the combination of a handle-bar provided with a longitudinal slot, 60 a revolute sleeve fitted upon the handle-bar, and provided with a spiral slot, a handhold secured to said sleeve, a plunger provided with a pin which operates in said slots, a 65 brake-shoe, a tube or guideway secured in the handle-bar and guide-post, and balls in said tube, interposed between the brake-shoe and the plunger for pushing the brake-shoe into operative position, and means for returning the brake-shoe, substantially as described. 70

In testimony whereof I hereunto affix my signature in presence of two witnesses.

JOHN C. ERNST.
